ELECTRIC PLUG BODY OR SIMILAR ARTICLE

Ralph A. W. Johanson, White Plains, and Jacques L. Le Baigue, Westbury, N.Y., assignors to Electrolux Corporation, Old Greenwich, Conn., a corporation of Delaware

Filed Sept. 9, 1964, Ser. No. 81,654

Term of patent 14 years

(Cl. D26—1)

Fig. 1

Fig. 2

Fig. 3

Fig. 4

Fig. 5

FIG. 1 is a front elevational view of an electric plug body or similar article showing our new design;

FIG. 2 is a side elevational view thereof;

FIG. 3 is a perspective view thereof;

FIG. 4 is a top plan view thereof; and

FIG. 5 is a bottom plan view thereof.

The plug prongs and a fragment of the electric cord are shown in broken lines for illustrative purposes only.

We claim:

The ornamental design for an electric plug body or similar article, as shown and described.
